INVENTOR.

UNITED STATES PATENT OFFICE.

CHARLES H. SUCH, OF PROVIDENCE, RHODE ISLAND, ASSIGNOR TO WIGHTMAN AND HOUGH CO., A CORPORATION OF RHODE ISLAND.

DESIGN FOR A BROOCH OR SIMILAR ARTICLE.

SPECIFICATION forming part of Design No. 36,094, dated October 7, 1902.

Application filed September 11, 1902. Serial No. 123,039. Term of patent 3½ years.

To all whom it may concern:

Be it known that I, CHARLES H. SUCH, a citizen of the United States, residing at Providence, in the county of Providence and State of Rhode Island, have invented and produced a certain new, original, and ornamental Design for a Brooch or Similar Article, of which the following is a specification.

In the drawings, Figure 1 is a face view of a brooch embodying my invention, and Fig. 2 a side elevation of the same.

As shown in the drawings, the leading or material features of my design are a plain face *c*, inclosed by a beading *a*, heart-shaped

in outline, and inclosed by an ornamentation *b* of foliates.

It is evident that my new design is applicable to pins other than brooches.

Having thus described my invention, what I claim is—

The ornamental design for a brooch or similar article as herein shown and described.

In testimony whereof I have affixed my signature in presence of two witnesses.

CHARLES H. SUCH.

Witnesses:

HORATIO E. BELLOWES,
FENNER JACKSON.
